UNITED STATES PATENT OFFICE.

GEORGE F. GODLEY, OF PHILADELPHIA, PENNSYLVANIA.

CAR-AXLE BOX.

SPECIFICATION forming part of Letters Patent No. 391,466, dated October 23, 1888.

Application filed May 5, 1886. Serial No. 201,213. (No model.)

To all whom it may concern:

Be it known that I, GEORGE F. GODLEY, a citizen of the United States, residing at Philadelphia, in the county of Philadelphia and State of Pennsylvania, have invented certain new and useful Improvements in Car-Axle Boxes, of which the following is a specification, reference being had therein to the accompanying drawings, wherein—

10 Figure 1 is a sectional elevation, showing axle-box, brass or bearing, axle, and cross-bar for receiving end-thrust of axle, embodying my improvements. Fig. 2 is a plan of bearing-surface of the brass. Fig. 3 is a sectional view similar to Fig. 1, showing brass and cross-bar for receiving end-thrust of axle, formed in one piece. Fig. 4 is a side elevation of axle-box, showing sliding lid. Fig. 5 is a perspective showing part of axle-journal 20 and of cross-bar, with lining or packing for receiving the end-thrust of the axle. Fig. 6 is a section on line 1 1, Fig. 4. Fig. 7 is a perspective of brass and of axle-journal partly broken away, and Fig. 8 is a sectional view of 25 a modified form of cross-bar for receiving end-thrust of axle.

My invention has relation to car-axle boxes in general, but more particularly to that form of same having sliding lids, dust-shields with 30 spring-pressure devices, and bearings or brasses having a self-lubricating lining or packing; and it has for its object simplicity and durability of construction of parts, whereby they are easily accessible for repairs or for 35 other purposes, dirt or dust is effectually excluded from the box, and the heating of the axle-journal in its brass or bearing or as it impinges against the brass or the cross-bar for receiving its end-thrust is avoided.

40 My invention accordingly consists of the combination, construction, and arrangement of parts, as hereinafter described and claimed, having reference particularly to a brass or bearing having on its under or bearing surface 45 depending side and edge flanges, diagonally-crossing ribs extending from corner to corner of said bearing-surface, and intermediate ribs connecting said diagonally-crossing ribs to the middle parts of the side and end flanges to 50 form a cluster of separate cells or chambers

for the reception of a filling or packing of self-lubricating material; to a brass or bearing having a lip or lug on its front end for engagement with a cross or end-thrust bar for the axle to keep said bar from rising vertically; 55 to the combination therewith of a cross-bar having a similar lining for receiving the end-thrust of the axle without generating friction or heat between the end of axle and cross-bar; to a bearing or brass having in its ends a filling or packing to avoid heating the collars or shoulders of the axle as it makes an end-thrust, and to a dust-shield having permanently attached to its front side spring-acting or pressure devices arranged to press the shield against 60 the inner side of the rear end of the box to close or seal the axle-opening therein.

In the drawings, A represents an axle-box, of any suitable or desired construction, having a front or lid opening, a, lid a', brass or bearing B, and a chamber, C, in its rear end; or the latter has double walls c c, if desired, with usual opening, c', for axle D. The journal d of the latter may be without a front end collar, or plain, as illustrated in Figs. 1 and 3, 75 or it may be made in the well-known manner, as partly indicated in Fig. 7.

The brass B is preferably formed on its under side with a series of approximately diagonally-arranged ribs, b and b', connecting the 80 ends and sides b² and b³, respectively. The main ribs b extend approximately from corner to corner of the brass, and the ribs b' from the center of the ends and sides of the brass to the middle of one-half of the ribs b, as shown more 85 plainly in Fig. 2, to form a central series or cluster of rhomboidal-shaped chambers or cells, b⁴, and an outer series of triangular-shaped chambers, b⁵, in the lower or bearing side of brass B, for the reception of a self-lubricating or other compound or material, E, for the axle-journal d. The intermediate ribs, b', are joined to the ribs b and to the edge flanges, as shown and described, to afford the requisite strength for the middle parts of said edge 90 flanges. Any suitable self-lubricating compound having for its basis asbestos, graphite, lamp-black, or equivalent substance combined by an indurating material is preferably used; but other suitable self-lubricating compounds 95 100

in contradistinction to soft anti-friction metals may be substituted. The lining or packing E is so placed in recesses or cells that it will project below the lower surfaces or edges of the 5 ribs b and b' and below the sides and ends of the brass B, as shown in Fig. 1, to prevent any part of the lower surface of the latter coming in contact with the axle-journal; but, if desired, the lower surfaces of said ribs and of the 10 packing or filling may be flush, as shown in Fig. 3. A brass B so constructed self-lubricates the journal d, and by reason of the latter not coming in contact with the brass itself all danger of heating of the latter is avoided.

15 The cross-bar F, for receiving the end-thrust of the axle D, is placed in the usual L or other appropriate side lugs, f, (see Fig. 1;) but this bar has on its side f', next to the end of the journal d, a recess, f'', in which is a packing or 20 lining of self-lubricating material, f'', as above described, for brass B, so that as the axle makes an end-thrust against bar F and its end revolves in contact therewith the packing f'' prevents the end of axle heating. This packing 25 in cross-bar F in relation to the end of the axle is more plainly shown in Fig. 5. If desired, the cross-bar recess f'' may be formed in a projection, f'', extending from the bar, as indicated in Fig. 8. When the bar F is used separately from the brass B, the latter has a projecting front lip, b', at its lower edge to keep the bar F from rising out of its guide or holding lugs f.

Instead of making the brass B and cross-bar 35 F in two pieces, they may be in one, as shown in Fig. 3, in which case the bar F is in the form of a lip depending from the brass, and it and the lip are held in position by the usual fastenings for the brass.

40 When no cross-bar F is used, and when an axle-journal having a collar at its front end is employed, the ends of the brasses are cut out or recessed, as shown at b', Fig. 7, and these recesses are filled with the packing or lining 45 E for lubricating the adjacent and contiguous edges or surfaces of the front and rear axle-collars, d' d'', respectively, during end-thrust of the axle.

Between the double wall c c, or in the end of 50 the box A, is located a flexible or other desired form of dust shield or plate, G, having axle-opening g, and upon its forward side permanently-attached springs g', of any suitable construction, which act to press the rear side, g'', of the shield against the inner side, c', of the 55 end of the box, as shown more plainly in Figs. 1 and 3, to close up the axle-opening c' in box A for effectually excluding dirt or dust from the same.

60 Any form of lid a' may be used; but I prefer to loosely secure it to the box, so as to slide up and down without being removed from the box. To do this I cast lugs or ribs h on the sides a' of the box adjacent to the edge of lid- 65 opening a, as shown in Fig. 4. These ribs h are wedge-shaped or taper from below upwardly,

and are embraced by an L-lug, a'', formed on each side of the lid and having rounded inner side, a'', for impingement with the back of the ribs h, as more plainly shown in Figs. 4 and 70 6, to keep the lid upon the ribs h and adapt it to easily slide thereon. The upper inner side of the ribs h is curved, as shown at h', to permit the lid as it is raised to be moved over the top of the box. The lugs a'' upon the lid are 75 relatively so arranged that when the lid is raised or opened, as shown in dotted lines x, Fig. 4, the upper edge of the lid strikes against the bearing-bars H of the box to prevent the lid moving off ribs h when raised; hence in 80 putting the box in position beneath a car the lids are affixed to the boxes before the bearing-bars H are inserted in place upon the boxes.

If desired, the sides of the boxes may have rearwardly-projecting flanges a'', as indicated 85 in the dotted lines, Fig. 4, or the long side of the lugs a'' may be continued to the top and bottom edges of the lid to cover the side joints between the lid and box for excluding dust therefrom. As the lid is lowered the lugs a'', 90 sliding down the wedge-shaped ribs h, draw the lid to the sides or edges of axle-box opening a to form a tight joint therewith. For convenience of moving the lid it is preferably provided with a push lug or knob, a'.

The diagonal arrangement of ribs b b' in bearing B affords the greatest possible extent of cell-space for the lining E without impairing the strength of the bearing and gives good or increased support for the lining in 100 the cells, so that it will be less liable to crumble or unduly wear under heavy pressure or other deteriorating causes incident to wear and tear.

The springs g', being permanently attached 105 to the shield G, make the latter complete in itself, and it requires no extraneous or independent devices attached to the axle-box for holding the springs and the shield in contact with the inner side of the rear wall of the box. 110

What I claim is—

1. A car-axle brass or bearing having on its under or bearing surface end and side flanges, diagonally-crossing ribs extending from corner to corner of said surface, short or intermediate 115 ribs connecting the diagonally-crossing ribs with the center parts of the end and side flanges to form a cluster of cells or chambers, and a packing or filling of self-lubricating material in said cells or chambers, substantially as set 120 forth.

2. A car-axle brass or bearing having on its under or bearing surface end and side flanges, b' b'', diagonally-crossing ribs b, extending from corner to corner of said surface, V-shaped ribs b', connecting the ribs b to the center parts of the flanges b' b'' to form a cluster of rhomboidal and triangular cells or chambers, and a packing or filling of self-lubricating material in said cells, substantially as set forth.

3. In combination with an axle-box and axle having inside lugs, f, a cross-bar, F, located in

front of the axle and supported on said lugs, and a packing or filling of self-lubricating material in said bar adjacent to the end of the axle, substantially as set forth.

5 4. A car-axle brass or bearing having in its ends open cells or recesses, and a lubricating filling or packing in said cells for oiling the adjacent axle-collar, substantially as set forth.

10 5. A car-axle brass or bearing having in its bearing surface or side cells or chambers, some of which extend out to the rear end of the axle-brass, and a lubricating filling or packing in said cells, substantially as set forth.

15 6. In an axle-box, the combination of a cross-bar, F, located in front of the axle end and having suitable supports in the sides of the box, a packing of self-lubricating material in the rear side of the bar F, adjacent to the end of the axle, and a brass or bearing, B, having 20 at its front end a projecting lip or lug, b⁶, which overlaps the top of bar F, substantially as and for the purpose set forth.

25 7. The brass B, having on its under side a self-lubricating filling or packing, E, combined with bar or lip F, having on its inner side a lubricating filling or packing, f³, substantially as set forth.

8. In combination with a car-axle box, a dust-shield having secured on its front side permanently-attached springs for pressing the 30 rear side of the shield against the inner side of the end of the axle-box, substantially as set forth.

9. An axle-box having rear double walls c c, shield G between the walls, and spring g', attached to the shield and located between the latter and the front wall c, as and for the purpose set forth.

10. An axle-box brass having front lip or lug, b⁶, in combination with separate cross-bar 40 F, having suitable supports, f, and a packing or filling, f³, substantially as set forth.

11. The combination, in a car-axle box, of a brass or bearing having a front lug or lip, b⁶, a cross-bar, F, beneath said lip, and supports 45 for said cross-bar, substantially as and for the purpose set forth.

In testimony whereof I affix my signature in presence of two witnesses.
